UNITED STATES PATENT OFFICE.

ABRAHAM COTLER, OF BROOKLYN, NEW YORK.

PENDANT WATCHCASE.

Application filed December 23, 1922. Serial No. 608,786.

To all whom it may concern:

Be it known that I, ABRAHAM COTLER, a citizen of the United States of America, and a resident of the borough of Brooklyn, 5 county of Kings, city and State of New York, have invented a certain Pendant Watchcase, of which the following is a specification.

This invention relates to pendant watch cases and especially to the class in which the dial side of the case has a face of any conventional form and the reverse side an ornamental reinforcement upon its upper edge and the upper portions of the side edges, 10 while the case is suspended at two points upon the upper edge, the whole forming a pendant and conveying the impression of a miniature hand bag or similar article.

The main object of the invention is to 20 introduce a novel form of utility into the class of pendant ornaments worn about the neck after the fashion of a lavallière.

Further objects and the particular advantages attained by my invention will be 25 come apparent as the specification proceeds.

In the accompanying drawing forming part of this application,

Fig. 1 is a view of a pendant watch case made according to my invention.

30 Fig. 2 is a reverse view of the same.

Fig. 3 is a view of another form of watch case including the features of my invention.

Fig. 4 is a reverse view of the same.

Fig. 5 is a side view of Fig. 1 with the 35 rear cover opened and in section to disclose the reinforced construction.

Fig. 6 is another modification of a watch embodying my invention.

Fig. 7 is a reverse view of the same.

40 Fig. 8 is a side view of Fig. 3 with both front crystal frame and rear cover partly opened.

Fig. 9 is a side view of Fig. 6.

Throughout the views, the same reference 45 numerals denote the same or corresponding parts.

In the field of pendant ornaments, it is customary to have mounted jewels and variously ornamented lavallières, lockets 50 and the like, but it is herein proposed to add to this class an article of novelty as well as utility which allows of many modifications and a great range of ornamental designs.

In the practice of my invention, a watch 55 1 is furnished with the usual dial 2, and with a winding stem 3. As the watch is to

be used as a pendant ornament, the upper portion has a pair of eyes 8, 8 to which are secured a pair of chains 9, 9 joined at the top by a common ring 10. If we neglect 60 the dial and the stem, the general appearance is that of a plain though very small hand bag, the surface being preferably ornamented in any desired manner. On the rear cover 6, an upper reinforcement 7 is located, 65 being a strengthening means as well as a means for simulating a mesh bag frame in construction and appearance. The front and rear covers 1 and 6, respectively, are hinged at 4 and 5 to the main body 15 of the 70 case, the front cover or frame 1 has the usual crystal 16 to protect the dial.

Another form is shown in Fig. 3, where the general outline of the case is a little more ornate, the reinforcement here taking 75 the form of frame 14 on the rear cover, 13. The crystal cover or frame 11 and the rear cover are hinged to the case body 20 as in the former case.

A third form which my invention may 80 take is shown in Figs. 6, 7 and 9, in which the crystal frame 17 and the rear cover 18 are hinged at 4 and 5 to a case 21, the rear cover here having a slightly different form 85 of reinforcement 19.

It may be noted that in each of the different forms of my invention, the back cover on a watch case is formed with a reinforcement of the whole upper edge, and in some possible construction it is also evident that the reinforcement may even occupy the upper portions of the side edges. 90

It is to be noted that in all the views a purse lock or clasp 12 is shown. This need not be actually useful in construction but merely be attached to heighten the resemblance between a watch case and hand bag. 95

Having thus fully described my invention, I claim,

1. A pendant watch case comprising a 100 case having a dial and upon its upper edge a suspension means, a crystal cover hinged to the case to cover said dial and a rear cover hinged to said case provided at the upper edge with a reinforced and raised portion. 105

2. A pendant watch case having a crystal frame upon one side, a cover on the reverse side provided with a raised reinforcement upon the upper edge thereof, and a purse lock upon the upper edge of said case. 110

3. A pendant watch case having upon one side a dial, a crystal frame to cover said

- 2
- dial and a cover on the reverse side provided at the upper edge and the upper portion of either side edge with a relief reinforced construction.
  - 5 4. A watch case having upon one side a dial and a cover therefor, a cover upon the reverse side, a relief reinforcement upon the upper edge of said reverse cover, a purse lock upon the upper portion of said case, and
  - 10 a winding stem projecting from one edge of said case.
  - 5. A watch case comprising an open face cover having a crystal, a corresponding op-

posite cover provided upon its upper edge with a reinforcement and a purse lock and 15 a winding stem upon the upper edge of said case.

6. A watch case comprising a dial side and a reverse side, a structure upon the upper portion of one of said sides to resemble a handbag flap, and a winding stem upon said case.

Signed at 4401 13th Ave., in the borough of Brooklyn, county of Kings, city and State of New York, this 21 day of December, 1922.

ABRAHAM COTLER.
